DESIGN FOR A COMBINED POPCORN CABINET AND DISPENSER OR SIMILAR ARTICLE

Harvey C. Wheeler, Brookline, Mass.

Application October 16, 1940, Serial No. 95,859

Term of patent 3½ years

To all whom it may concern:

Be it known that I, Harvey C. Wheeler, a citizen of the Principality of Monaco, residing at Brookline, in the county of Norfolk, in the Commonwealth of Massachusetts, have invented a new, original, and ornamental Design for a Combined Popcorn Cabinet and Dispenser or Similar Article, of which the following is a specification, reference being had to the accompanying drawing, forming a part thereof.

I claim:

The ornamental design for a combined popcorn cabinet and dispenser or similar article, substantially as shown.

HARVEY C. WHEELER.
